SAW TOOTHED WAVE GENERATOR

Hanswerner Pieplow, Berlin, Germany, assignor
to Allgemeine Elektricitäts-Gesellschaft, Berlin, Germany, a corporation of Germany

Application April 26, 1937, Serial No. 139,026
In Germany April 25, 1936

1 Claim. (Cl. 250—36)

(Granted under the provisions of sec. 14, act of
March 2, 1927; 357 O. G. 5)

This invention relates broadly to an apparatus for generating sawtoothed or serrated electrical waves and more particularly to an apparatus by means of which high frequency waves of this nature which are particularly suited for use with cathode ray apparatus may be generated.

For the generation of sawtooth waves, also known as ratchet or relaxation waves of very high frequency, recourse is had as a general rule to high vacuum tubes.

My invention will best be understood by reference to the following figures in which

Fig. 1 shows an arrangement of the prior art, Figs. 2, 3 and 4 are explanatory curves, and Fig. 5 is an embodiment of my invention.

Fig. 1 shows a circuit arrangement of the prior art. The condenser 1 is charged up by the charge tube 2 with a constant current. During this time, the grid of the control tube 3 is at filament or cathode potential, with the result that the fall of potential occasioned by the passage of the plate current of tube 3 through the resistance 4 imparts to the tube 5 a negative grid biasing voltage. The discharge tube 5 (ratchet tube) stays blocked until the condenser 1 is charged up; and it is only then that the potential difference between plate and filament of tube 5 has grown sufficiently high to drive a current through the tube 5 or in other words to render tube 5 conducting. However, at the instant when tube 5 becomes conducting, the condenser 6 which has been charged up to full potential is discharged and the discharge current through leak resistance 7 allows the grid of tube 3 to become negative, thereby diminishing the plate current through tube 3 and increasing the grid potential of tube 5 in the positive sense. In this manner, the internal resistance of tube 5 is reduced and the discharge current of condenser 1 through tube 5 grows very rapidly with the consequence that the condenser is discharged at a fast rate of speed.

If the different circuit elements have been suitably dimensioned, the rate of speed of the said discharge depends, in the last analysis, only upon the characteristics of the tubes that have been employed. Control tube 3 is required to satisfy only the demand of great slope of its characteristic in order that it may respond with sufficient strength even to the least grid potential variations. For this reason, it could well be of the pentode type. The discharge tube 5, on the contrary, should not be a pentode in the present circuit scheme, firstly, because the tube 5 should start operating only in the presence of a definite

voltage of finite value across the condenser 1, and that, secondly, all plate current-plate potential characteristics of a screen-grid tube originate at zero point. The use of a triode or three-electrode tube which thus becomes imperative occasions a retardation of the incipient discharge for several reasons.

Referring to Fig. 2, there is shown the characteristic curves of a triode tube. If the potential across the condenser 1 and thus the plate potential across tube 5 undergo an increase, it will be seen that owing to the curvature of the characteristic the discharge current through tube 5 begins at low values and through a very high internal resistance du_a/di_a so that initially the influence on the control tube 3 and regeneration or feedback to the grid of tube 5 stay low.

Referring to Fig. 3, there is illustrated by means of the shape of the condenser potential the results obtained in practice. The discharge is initiated in a somewhat lagging and wavering way, attains a maximum rate of speed and discontinues again (also because of the curvature of the characteristic) in a lagging manner. Inasmuch as the total discharge period t is governed by the tube mechanism and may not be reduced and since t , on the other hand, must be small in contrast with the charge period, there results a very definite minimum period for the charge, that is to say, a very definite maximum value for the sawtooth wave frequency, if the shape of the sawtooth wave is to be acceptable and suitable, say, for oscillographic work. The limiting frequency is of an order of magnitude around 0.5 megacycle.

Now, it will be understood that the said limiting frequency may be raised if the discharge tube for small plate currents has a low value of du_a/di_a . According to this invention, therefore, the discharge period is abbreviated by using for the discharge tube (ratchet tube) a pentode type of tube, while the zero point of the plate current-plate potential diagram is shifted in the negative sense by the introduction of a controlled auxiliary voltage.

Referring to Fig. 4, the principle underlying the idea is illustrated which represents the family of curves for a standard screen-grid tube. If, then, the ordinate axis is shifted a distance $-u_c$ into the position indicated by the broken line, the condenser may be charged up to the potential $+u_c$. The screen-grid tube will now respond with a far stronger current than a triode tube, so that the biasing voltage $-u_c$ can be driven down to zero at a far more rapid rate.

50

55

Referring to Fig. 5, there is shown an exemplified embodiment of the arrangement according to this invention. The current of the control tube 3 sets up across the resistance 9 a biasing potential $-u_c$ which disappears upon blocking of the tube 3 in accordance with the above described control action through the condenser 6 and the leak 7. Inasmuch as tube 3 is fed back to the plate circuit of pentode 8, the connection of the control grid of tube 8 is immaterial. Also, tube 3 could be a screen-grid tube. Synchronizing means could suitably be inserted in the screen-grid circuit of tube 8.

What I claim is:

An oscillation generator comprising a condenser, means for storing electrical energy in said condenser, a discharge path for said con-

denser comprising a multi-grid vacuum tube having a cathode, anode and at least three grids having its plate and cathode connected across said condenser, means for connecting one of said grids directly to said cathode, means for biasing another of said grids positive with respect to said cathode, a second vacuum tube having anode, cathode and at least one control electrode, means for coupling another of the grids of said first tube to the anode of said second tube and the anode of the first tube to the control electrode, and means for coupling the anode of the second tube to the anode of the first tube comprising resistance means in a common path between said means for storing energy and the anodes of both tubes.

HANSWERNER PIEPLOW.
